US00D765714S

(12) United States Design Patent (10) Patent No.: US D765,714 S
Moon et al. (45) Date of Patent: * Sep. 6, 2016

(54) DISPLAY SCREEN OR PORTION THEREOF
WITH GRAPHICAL USER INTERFACE

(71) Applicant: Samsung Electronics Co., Ltd., Suwon-si, Gyeonggi-do (KR)

(72) Inventors: Joo-Sun Moon, Seoul (KR); Pill-Kyong Moon, Seoul (KR); Ji-Min Hong, Yongin-si (KR); Se-Ran Jeon, Seoul (KR)

(73) Assignee: SAMSUNG ELECTRONICS CO., LTD., Suwon-Si, Gyeonggi-Do (KR)

() Term: 14 Years

(21) Appl. No.: 29/492,719

(22) Filed: Jun. 2, 2014

(30) Foreign Application Priority Data

Dec. 3, 2013 (KR) 30-2013-0060782

(51) LOC (10) Cl. 14-04

(52) U.S. Cl.

USPC D14/487

(58) Field of Classification Search

USPC D14/485-495; D18/24-33; D20/11, 12,

D20/18, 22-28; 715/700-867, 961-978

CPC .. G06F 3/0482; G06F 3/048; G06F 3/04817;

G06F 3/0481

(57) CLAIM

The ornamental design for a display screen or portion thereof with graphical user interface, as shown and described.

DESCRIPTION

The sole FIGURE is a front view of a display screen or portion thereof with graphical user interface, showing our new design.

The broken line showing of the display screen and elements of the graphical user interface is intended for the purpose of illustrating portions of the article and form no part of the claimed design.

1 Claim, 1 Drawing Sheet
